BATTERY FRAME FOR A HEARING AID

William J. Field and Norman J. Quam, Minneapolis, Minn., assignors to Lectro Company, Minneapolis, Minn., a copartnership composed of William J. Field, Norman J. Quam, and Le-land A. Watson

Application March 6, 1939, Serial No. 260,080

3 Claims. (Cl. 136—171)

Our invention relates to improvements in battery frames and, more particularly, to a battery frame for holding the A and B batteries of a hearing aid.

It is an object of this invention to provide an extremely simple and highly efficient battery frame that will hold an A battery and a B battery in compact arrangement, whereby the same may be readily carried in the pocket of a garment or attached to a belt by means of a clip.

A further object of the invention is to provide a battery frame that is very light in weight and in which the batteries may be quickly and easily removed and new ones substituted therefor.

A still further object of the invention is to provide a frame for the A and B batteries in which either thereof may be removed from the frame simply by pulling or lifting the respective battery.

To the above end, generally stated, the invention consists of the novel devices and combinations of devices, as well as the novel construction and arrangement of parts hereinafter described and defined in the claims.

In the accompanying drawings, which illustrate the invention, like characters indicate like parts throughout the several views.

Referring to the drawings:

Fig. 1 is a view in elevation showing a complete vacuum tube hearing aid, with portions of the electric wires, that connect the several in the "A battery" shown therein by means of broken lines;

Fig. 2 is a front end elevation of the battery frame with the "B battery" separated therefrom;

Fig. 3 is a plan view of the battery frame with the "A battery" shown therein by means of broken lines;

Fig. 4 is a rear end elevation of the amplifier;

Fig. 5 is a left hand side elevation of the amplifier, as shown in Fig. 4;

Fig. 6 is a view, partly in end elevation and partly in section, taken on the irregular line 6—6 of Fig. 1;

Fig. 7 is a fragmental front elevation of the amplifier, with some parts broken away and sectioned on the line 7—7 of Fig. 5 to expose the volume control;

Figs. 8 and 9 are views, partly in plan and partly in section, taken, respectively, on the line 8—8 and 9—9 of Fig. 6;

Fig. 10 is a rear end elevation of the battery frame with the "B battery" removed therefrom, and also showing by means of full and broken lines, a pair of filler plates attached to the inner

faces of the jaws of the clip that holds the "B battery"; and

Fig. 11 is a fragmentary plan view of the amplifier as shown in Fig. 4, with the cover partly removed.

The improved hearing aid comprises three units to wit: an ear phone or receiver, an amplifier, and a metallic battery frame, indicated, as entireties, by the numerals 12, 13, and 14. The various elements which go to make up the amplifier 13 are contained within a round box or case 15 having a removable cover 16 that is held thereon by a capping flange. On the back of the amplifier 13, is a spring clip 17 for use in attaching said amplifier to a pocket or other part of a person's clothing or to a belt.

For the purpose of this case, it is not thought necessary to show the output circuit of the amplifier 13 except the sockets 18 mounted in the side of said amplifier at the top thereof. The ear phone 12 is connected to the output circuit by a pair of wires 19 having on their ends, at the amplifier 13, a plug 20, the prongs of which are removably held in sockets 18 of the output circuit. The flange of the cover 16 is notched at 21 to afford working clearance for the sockets 18, during the application of said cover to the case 15 or the removal of the same therefrom.

Within the case 15 is a control switch, not shown, the movable member of which includes a button-like finger piece 22 on the outer side of the case 15, at the top thereof. The neck of the finger piece 22 works in a slot 23 which extends circumferentially in the side of the case 15. A T-shaped notch 24 in the flange of the cover 16 affords working clearance for the neck of the finger piece 22 and also permits the application of the cover 16 to the 15 or its removal therefrom.

For the purpose of this case it is not thought necessary to show the different elements that go to make up the amplifier 13, except the volume control 25; see Fig. 7. The movable member of the volume control 25 is operated by a wheel 26, the rim portion of which works in and extends outwardly of a slot 27 that extends circumferentially in the side of the case 15 between the sockets 18 and the finger piece 22. Obviously, the wheel 26 may be easily operated by the thumb. The flange of the cover 16 is notched at 28 to afford working clearance at the wheel 26 to permit the application of the cover 16 to the case 15, or the removal of the same therefrom.

In the face of the cover 16 is a grill 29 that affords a sound passageway.

The source of the electrical energy for the amplifier 13 is supplied thereto by an "A battery" 30 and a "B battery" 31. These batteries 30 and 31 are removably mounted in the frame 14 and which frame has an open top compartment 32 for holding the "A battery" 30 and a clip 33 for holding the "B battery" 31. Pressed from the rear end member of the frame 14, is a negative contact 34 that projects into the compartment 32. A yoke-like spring positive contact 35, within the compartment 32, is secured to the front end member of the frame 14 and insulated therefrom. On the bottom of the compartment 32 is a fibre plate 36 on which the "A battery" 30 rests in a horizontal position with its positive terminal in engagement with the spring contact 35. This spring contact 35 yieldingly presses the "A battery" endwise toward the rear end member of the compartment 32 and holds the same with its negative terminal in engagement with the contact 34.

The sides of the compartment 32 extend upwardly substantially half way to the upper side of the "A battery" 30 and the end members of said compartment, above the sides thereof, are semi-circular and extend to the upper side of said battery. The "A battery" 30, which is cylindrical, snugly fits between the sides of the compartment 32 and is thereby held from rolling out of engagement with the contacts 34 and 35. In the sides of the compartment 32 are deep notches 37 that afford clearance for the fingers when gripping the sides of the "A battery" to lift the same from the compartment 32.

The clip 33 comprises a pair of flat spring jaws 38 which frictionally hold the "B battery" clamped therebetween. These jaws 38 are depending extensions of the sides of the compartment 32 and extend the full length thereof. The jaws 38 are in slight downwardly converging relation and their lower longitudinal edge portions are curved slightly outwardly, as indicated at 39.

Upper and lower fibre plates 40 are secured to the bottom of the compartment 32 between the jaws 38 by eyelets 41, which also secure the plate 36 on the bottom of the compartment 32. Obviously, the curved lower edges 39 of the jaws 38, facilitate the insertion of the "B battery" 31 between the jaws 38 and thereby spring the same apart and place said jaws under sufficient tension to frictionally hold said battery. The jaws 38 are capable of holding "B batteries" of different lengths and widths. To adapt the jaws 38 for holding "B batteries" of different thicknesses, a fibre filler plate 42 may be secured to the inner face of either one or both of the jaws 38. In Fig. 10, two of the filler plates 42 are shown; one by full lines and the other by broken lines. These filler plates 42 are secured to the jaws 38 by eyelets 43 which extend through holes 44 in the lower corners of the jaws 38.

The two contact plates 45 on the top of the "B battery," engage spring projected contacts 46 mounted for endwise sliding movement in eyelets 47 secured to and extending transversely through the lower fibre plate 40. Apertures 48 are formed in the inner fibre plate 40 and the bottom of the compartment 32 to afford clearance for the inner end portions of the contacts 46.

Mounted in the front end of the compartment 32 are four sockets 49, two of which are the terminals for the "A battery" and are connected, the one to the battery frame 14 and the other

to the positive contact 35. The other two sockets 48 are terminals of the "B battery" and are connected by a pair of wires 50, indirectly to the spring projected contacts 46 through the eyelets 47 to which said wires are attached.

Four sockets 51 extend through an aperture in the side of the case 15 at the bottom thereof. Two of these sockets 51 are terminals for the filament supply and the other two thereof are terminals for the plate supply. Both the filaments and the plates are within the case 15, but are not shown. Wires 52 have on one side of their ends a plug 53 and on their other ends a plug 54, with the prongs of the first noted plug fitted into the sockets 49, and with the prongs on the last noted plug fitted into the sockets 51. These wires connect the "A battery" 30 to the filaments supply and the "B battery" 31 to the plates.

The mounting of the switch finger pieces 22 and the wheel 26 on the perimeter of the amplifier 13 is important, as it positions the same where they may be easily manipulated. Furthermore, this mounting of the finger piece 22 and the wheel 26, positions the same where they are not liable to be accidentally moved by a piece of clothing covering the amplifier 13.

It is well known that an amplifier is usually worn where the same can be covered by a piece of clothing. By mounting the finger piece 22, the wheel 26, and the plugs 20 and 53 on the perimeter of the amplifier, the face of said amplifier is left smooth, so that an overlying garment may fit smoothly thereover and is not held at an unnecessary distance from the body.

The frame 14 holds the two batteries in compact arrangement so that said frame and batteries may be easily carried in a pocket or otherwise on the body, without causing the undue bulging of clothing therefrom. As heretofore stated, the clip 33 will hold batteries of various lengths and widths by the use of one or more of the filler plates 42, and the jaws 38 will securely hold batteries of different thicknesses.

The drawings illustrate a commercial form of the invention, but it will be understood that the same is capable of certain modifications as to details of construction, arrangement of parts and combination of parts within the scope of the invention herein disclosed.

What we claim is:

1. A battery frame of conducting material for a hearing aid and having a cradle-like compartment holding a cylindrical A battery horizontally disposed therein, an insulating member in said compartment on which the A battery rests, electrical connections for the A battery including a pair of contacts in the compartment with which the terminals of the A battery engage, one of said contacts being insulated from the frame and the other thereof being in contact therewith, one of said contacts being a spring, said frame also having a pair of spring metal jaws for engaging the sides of a rectilinear B battery inserted therebetween and held suspended at the under side of the bottom of the compartment, said jaws forming depending extensions of the sides of the compartment, the space between the jaws being unobstructed whereby the B battery may be inserted upwardly between the jaws, a pair of insulating members between the bottom of the compartment and the top of the B battery, and electrical connections for the B battery including a pair of contacts on the under side of the pair of insulating members constructed and arranged

to be engaged by the terminals of the B battery and a pair of leads interposed between the pair of insulating members and attached one to each of the contacts for the B battery.

2. The structure defined in claim 1 in which the compartment has ends, the upper portions of which are segmental and extend substantially to the top of said A battery in the compartment, and in which the compartment has sides, the upper edges of which are substantially in a horizontal plane that extends through the axis of said A battery, the sides of the compartment having intermediate finger notches.

3. The structure defined in claim 1 in which the length of the jaws corresponds to the length 15

of said B battery, and in which the spacing of the contacts on the under side of said pair of insulating members corresponds to the spacing of the contacts on said B battery, whereby when said B battery is inserted between the jaws with its minus and plus contacts in the same position as the corresponding contacts on the under side of said pair of insulating members and with its ends aligned with the ends of the jaws, the contacts on said B battery will engage the contacts on the under side of said pair of insulating members.
